[57] CLAIM

The ornamental design for a splash resistant pet dish, as shown and described.

DESCRIPTION

FIG. 1 is a front perspective view of my new design of the splash resistant pet dish;

FIG. 2 is a front elevational view thereof, the rear view being identical thereto;

FIG. 3 is a left side view thereof, the right side view being identical thereto;

FIG. 4 is an overhead plan view of the dish of the invention; and,

FIG. 5 is a bottom view thereof.

FIG. 1

FIG. 2

FIG. 3

FIG. 4

FIG. 5
